(57) **CLAIM**

The ornamental design for a video conference device, as shown and described.

DESCRIPTION

FIG. 1 is a front, right, top perspective view of a video conference device showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a partial enlarged view of an area labeled 8 in FIG. 1.

The evenly-dashed broken lines depict portions of the video conference device that form no part of the claimed design. Moreover, an array of circular features near a base of the video conference device in FIGS. 1-6 and 8 that are depicted with the evenly-dashed broken lines form no part of the claimed design. The dot-dash broken lines, as shown in FIGS. 1 and 8, that frames portions of the video conference device for enlargement purposes form no part of the claimed design.
